RANGE DRAFT CONTROL

Robert C. Lang, Kalamazoo, Mich., assignor to
Kalamazoo Stove & Furnace Co., Kalamazoo,
Mich.

Application June 14, 1946, Serial No. 676,788

3 Claims. (Cl. 126—1)

1

This invention relates to improvements in range draft control.

The principal objects of this invention are:

First, to provide a wood or coal burning range with draft and heat control dampers on the rear wall thereof so that the front of the range will have a neater appearance, more closely resembling a gas or electric range.

Second, to provide control linkage for the draft and heat control dampers of a range permitting the operating handles to be positioned on the side of the range.

Third, to provide control linkage for the dampers of a range which will be effectively concealed between the top of the range and the decorative end panel.

Other objects relating to the details and economies of the invention will be apparent from the following description.

In the drawings, of which there are two sheets:

Fig. 1 represents a plan view partially broken away of a range having my system of damper controls installed thereon.

Fig. 2 represents an end elevational view of the range shown in Fig. 1 with the top panel cut away.

Fig. 3 represents an enlarged plan view of the control mechanism shown in Fig. 1.

Fig. 4 represents a perspective view from the rear corner of the range showing the damper control mechanism as installed thereon.

Fig. 5 represents a cross-sectional view taken along the line 5—5 in Fig. 3.

The stove or range on which the controls are installed consists of a sectional top member 1 supported on the front frame member 2, rear frame member 3 and end frame member 4. Fire-pot panels 5 are positioned in one end of the range and the upper wall 6 of an oven positioned in the center of the range coacts with the range top, front and rear frame members to form a flue 7 through which the hot gases from the fire are directed to reach the smoke chamber 8 positioned on the back of the range. The details of construction of the ranges are more particularly described and claimed in the copending application of James M. Cook, Shirly C. Salter, and myself, Serial No. 684,560, filed July 18, 1946, owned by the same assignee. For the purpose of this application it is sufficient to state the flue 7 extends around the top, side, and bottom of the oven 6 and communicates with the smoke chamber 8 through a constantly open passage at the bottom of the oven

2

and through an upper passage opening over the top of the oven and controlled by the damper 9.

The end of the range is closed by a decorative end panel 11 and a rear panel 12 which latter panel defines a flanged draft opening 10 controlled by the damper 13. By means of these dampers, air may be admitted to the bottom of the combustion chamber and the hot gases may be directed around three sides of the oven or by-passed directly into the smoke chamber.

A bracket 14 is secured to the rear wall of the range and pivotally supports one end of the oven heat control shaft 15. Secured to the end of the shaft 15 is a U-shaped lever 16 provided with the crank arm 17. The crank arm 17 is pivotally connected with a link 18, the other end of which is connected to the L-shaped lever 19, non-rotatably secured to the oven damper shaft 20. The oven damper 9 is provided with ears secured to the shaft 20 so that rotation of the shaft will open or close the damper. The opposite end of the oven heat control shaft 15 is pivotally supported in the end frame member 4 and has a crank 21 securely fastened thereto.

A second bracket 22 is secured to the rear wall of the range and pivotally supports the draft control shaft 23. One end of the shaft 23 is shaped in the form of a crank 24, the arm of which is pivotally connected to the draft link 25 extending downwardly to the crank arm 26 formed on the draft damper 13. The damper 13 is formed as a stamping and is provided with a flanged edge 27, the ends of which are bent backwardly and apertured to pivotally support the damper on the shaft 28. The shaft 28 is supported between the legs of the U-shaped bracket 29 welded to the rear wall 12 of the furnace. The opposite end of the draft damper control shaft 23 has the crank member 30 non-rotatably secured thereto.

An oven heat control push-rod 31 is pivotally connected to the crank 21 and a draft control push rod 32 is pivotally connected to the crank 30. The push rods 31 and 32 extend forwardly along the side frame member 4 and underneath the end of the range top 1. Near their forward ends the push rods are provided with depending fingers 33 terminating in horizontally extending flanges 34 which extend outwardly through the slot between the range top 1 and the decorative end panel 11. Suitable control knobs 35 are secured to the ends of the flanges 34 and appropriately marked as indicated in the drawings. The bodies of the push rods are embossed in stiffening ridges 36.

The inner ends of the flanges 34 are supported upon the lower flange of an angle bracket 37, the vertical side of which is welded to the side frame member 4 of the range. The vertical flange of the angle bracket is cut away and passed outwardly toward the end of the range in a series of ears to form damper control stops 38 and draft control stops 39. The stops 38 have horizontal portions which support the forward end of the damper control rod 31 and engage the finger 33 thereon to limit the forward and rearward movement of the damper control rod. Vertical portions of the stops retain and space the damper control rod from the draft control rod 32. The stops 39 are bent further out from the end frame of the range and retain the forward end of the draft control rod in place. The vertical flange of the bracket 37 is pressed outwardly from the range between the draft stops as at 40 to form the back of a slot in which the draft control rod is slid able.

The controls are thus arranged so that pushing back on the draft knob will raise the draft damper to admit air to the fire chamber and pushing the damper control rod back will open the oven heat control damper to by-pass the hot gases into the smoke chamber 8.

The arcuate portion 41 on the crank 30 is provided with an arcuate slot 42 through which the bolt 43 extends to the bracket 22. The bolt is used for loading the spring 44 to frictionally hold the draft damper 13 in any position of adjustment.

Having thus described my invention, what I claim as new and desire to secure by Letters Patent is:

1. A solid fuel burning range comprising an end frame member, a rear panel member defining an air inlet passage and a smoke outlet passage, a pair of dampers positioned on said rear panel member for closing said passages, linkage for operating said dampers supported upon said rear panel member, control rods for selectively actuating said linkage and positioned along said end frame member and having depending fingers on the forward ends thereof, a bracket of angle-shaped cross-section secured to said end frame member and supporting said fingers upon its lower flange, a pair of stop members bent from the vertical flange of said bracket and arranged to engage the finger on one of said control rods to limit the movement thereof, and another pair of stop members bent from the vertical flange of said bracket and ar-

ranged to limit the movement of the finger on the other of said control rods, said pairs of stop members being spaced in different planes to retain the forward ends of said control rods in spaced parallel relationship.

2. The combination with a solid fuel burning range having an end frame member with a top member and end closure panel supported thereon, of a down turned flange on said top member terminating in substantial flush vertically spaced relationship with said end panel, an air inlet damper positioned on the rear of said range, a smoke by-pass damper positioned on the rear of said range, linkages for operating said dampers including a pair of control rods positioned along said end frame member and between said top member and end panel, said control rods having fingers extending outwardly of said range between said flange and said end panel and near the forward end thereof, and control knobs positioned on the ends of said fingers.

3. The combination with a solid fuel burning range having an end frame member with a top member and end closure panel supported thereon, of a down turned flange on said top member terminating in substantial flush vertically spaced relationship with said end panel, an air inlet damper positioned on the rear of said range, a smoke by-pass damper positioned on the rear of said range, linkages for operating said dampers including a pair of control rods positioned along said end frame member and between said top member and end panel, said control rods having fingers overlying the top of said end panel and extending outwardly of said range between said flange and said end panel and near the forward end thereof, and control knobs positioned on the ends of said fingers.
